UNITED STATES PATENT OFFICE

RUDOLPH BECKER, OF NORTH PLAINFIELD, NEW JERSEY, ASSIGNOR TO THE SINGER MANUFACTURING COMPANY, OF ELIZABETH, NEW JERSEY, A CORPORATION OF NEW JERSEY

CHAIN-STITCH SEWING MACHINE

Application filed June 22, 1927. Serial No. 200,592.

This invention relates to sewing machines and has for an object to provide a simplified, quiet running mechanism for forming a chain-stitch seam, which mechanism is capable of high-speed operation.

In chain-stitch sewing machines it is usual to provide a reciprocating needle for passing needle-thread loops through the work and a looper for presenting the needle-loops, or loops of an under thread enchained with the needle-loops, for entry by the descending needle. In one known type of looper mechanism the looper is actuated by two cranks or eccentrics, one of which imparts to the 10 looper loop-seizing and -shedding movements and the other of which gives the looper sidewise or so-called "needle-avoiding" movements, whereby the looper passes along one side of the needle, seizes a needle-loop and 15 moves to the end of its stroke; is then given a sidewise movement and is retracted along the other side of the needle-path.

In another known type of looper mechanism the looper is given its loop-seizing and 20 -shedding movements in a single plane and a spreader is introduced to assist in positioning the thread-loop for entry by the needle.

With machines of the above types, where the looper is actuated by one or more simple 25 crank motions, it is necessary to increase the amplitudes of motion of the needle and looper sufficiently to secure the proper relative timing of these implements at two points in the stitch-forming cycle, to wit: *a*, when the 30 looper seizes a needle-loop and *b*, when the needle enters the loop positioned by the looper.

It has been proposed to reduce the amplitudes of motion of the needle and looper by 35 modifying the actuating mechanism so as to give the looper an irregular motion including dwells and periods of rapid motion, but such irregular motion can only be secured by the use of cams, toggle devices, etc., which 40 complicate the actuating mechanism and are mechanically inferior to simple crank-motions.

It has also been proposed to solve the 45 problem of simplicity and high speed by providing two separately timed implements be-

low the work, one a loop-taking implement which carries no thread and is crank operated and properly timed to enter and detain the needle-loop, and the other, a crank operated thread-carrying looper for passing a 55 looper-thread loop through the needle-loop while held by the loop-taker, after the needle has risen from the work; the thread-carrying looper being timed to present its loop to the descending needle. But little has been 60 done toward developing machines involving the last above proposed method, and such machines as have been developed are unsatisfactory at high speeds for several reasons among which may be mentioned: 1. The 65 needle-loop is needlessly expanded or drawn out and causes undue reeling of thread through the needle-eye. 2. In some cases the loop-taker is depended upon to drag the looper-thread loop through the needle-loop, 70 which necessitates a harsh or sudden engagement of the loop-taker with the looper-thread, tending to unduly strain the latter. 3. The loop-taker twists the loops and thus introduces a tendency of such loops to kink or 75 snarl while being drawn up.

According to the present improvement there are provided separately timed loop-taking and loop-presenting implements. The 80 loop-taker has a slender thread-engaging portion which moves in the direction of its length and seizes a needle-loop without twisting or expanding such loop. The loop-presenter is preferably a simple two-motion 85 thread-carrying blade which passes a loop of under-thread through the needle-loop and is timed to present the under-thread loop to the descending needle.

The present machine is a further development of that disclosed in my copending application Serial No. 137,863, filed September 7, 1926. In my prior machine the loop-taker is in the form of a continuously rotating ring supported by a circular raceway, while in the present machine the loop-taker is in the form 95 of an oscillatory finger carried by a rock-shaft. The loop-taker and loop-presenter or looper elements of the present machine preferably operate in substantially coincident planes at the same side of the needle-path 100.

and substantially parallel to the line of feed. As in my prior machine, the loop-taker is a slender bodied implement which seizes and detains a needle-loop without expanding such loop, whereby reeving of the needle-thread is reduced to a minimum. The loop-taker and loop-presenter elements are preferably mounted on coaxial shafts which are driven by crank and pitman connections from actuating eccentrics on the main-shaft.

10 A feature of the present machine lies in the ease with which the mechanism may be adapted for use with a plurality of needles of any desired gauge or spacing between the needles; the loop-taker and loop-presenter or looper elements being individually secured to parallel supporting studs carried by the respective shafts and being adjustable lengthwise of such studs to suit the needle positions.

15 As these elements may be made comparatively thin, they may be secured close together for narrow gauge requirements.

20 The machine is provided with a novel form of multiple thread tension release connected to be operated by the presser-foot lifting-lever. A novel form of multiple looper-thread guide is also provided to facilitate easy threading and prevent entanglement of the looper-threads.

25 30 In the accompanying drawings, Fig. 1 is a side elevation, partly in section, of a sewing machine embodying the invention. Fig. 2 is a bottom plan view of the machine. Fig. 3 is a view of the rotary needle-thread take-up. Fig. 4 is a section on the line 4—4, Fig. 1. Fig. 5 is an end elevation of the cylinder-bed of the machine showing the stitching-forming mechanism; the needles just beginning their rising movement. Fig. 5^a is a side view of the needles and loop-takers looking oppositely to the direction of feed at the time of the cycle shown in Fig. 5. Fig. 6 is a view similar to Fig. 5 but at a later stage in the stitch-forming cycle; the needles rising above the work and the loop-takers detaining the needle-loops without having expanded such loops. Fig. 6^a is a side view of the parts shown in Fig. 6 looking in the direction of feed. Fig. 7 shows the stitch-forming elements with the needles at the top of their stroke; the loopers having entered the detained needle-loops and the loop-takers retracting. Fig. 8 shows the needles descending and the loop-takers and loopers both retracting. Fig. 9 shows the needles entering the looper thread-loops, the loopers retracting and the loop-takers reversing or at their dwell point. Fig. 10 is a perspective view of the looper carrier with one of the loopers removed. Fig. 11 is a perspective view of the looper removed from the looper carrier. Fig. 12 is a top plan view of the throat-plate. Fig. 13 is a section on the line 13—13, Fig. 12. Fig. 14 is a section on the line 14—14, Fig. 12. Fig. 15 is a transverse section

70 through the loop-taker driving shaft and the hub of the looper carrier. Fig. 16 is a top plan view of the multiple needle-thread tension device. Fig. 17 is a central transverse vertical section through the tension device. Figs. 18 and 19 are perspective views of the tension release cam and cam-follower. Fig. 20 is a rear view of the machine bed showing the looper-thread tensions and looper-thread guide. Fig. 21 is a perspective view of the 75 looper-thread guide removed from the machine, and Fig. 22 is a section on the line 22—22, Fig. 20.

80 In the preferred embodiment of the invention illustrated, the machine comprises a frame having a base 1 formed with a horizontally extending cylinder-bed 2. Rising from the base 1 is the standard 3 of the overhanging goose-neck 4 terminating in the head 5. Journaled in the goose-neck 4 is the main-shaft 6 carrying at its forward end the rotary needle-thread take-up 7 and having the usual crank-and-link connection 8 with the needle-bar 9 carrying three needles 10 arranged in a plane transverse to the line of feed.

85 Journaled in the bed 2 are the coaxial, oscillatory, solid and hollow shafts 11, 12; the shaft 11 having mounted on its front end the loop-takers 13, the upper or working extremity of each of which is bent over to form a slender-bodied loop-seizing portion 14 which moves in the direction of its length to seize a needle-loop without expanding such loop.

90 95 Clamped to the front end of the hollow shaft 12 is the split collar 15 to which is fixed the stud 16 in parallelism with the shaft 11; the collar 15 and stud 16 constituting a carrier for the loop-presenters 17, in the form of thread-carrying loopers, the blades of which are disposed in parallel planes substantially coincident with the planes of the loop-takers 14—the loopers 17 working close to the throat-plate 18. The rock-shafts 11, 12 are operated, respectively, by eccentrics 19, 20 on the main-shaft, which eccentrics 100 actuate the pitmen 21, 22 connected at their lower ends to cranks 23, 24 carried by the shafts 11, 12. The eccentric 19 is timed to cause the loop-takers to seize the loops of thread thrown out by the rising needles, as shown in Figs. 5 and 5^a, and the eccentric 20 is timed independently of the eccentric 19 to cause the loopers 17 to retract and open the looper-thread loops at the proper moment to be entered by the points of the descending needles, as shown in Figs. 8 and 9.

105 115 120 The feeding mechanism comprises the feed-dog 25 mounted on the feed-bar 26 which is pivotally supported at 27 by a crank-arm 28 on the feed-lift rock-shaft 29. Connected to the feed-bar at 30 is a link 31 which is connected at 32 to a crank-arm 33 on the feed-advancing rock-shaft 34. The

feed rock-shafts 29, 34 extend lengthwise of and within the cylinder-bed 2 and at their rearward ends carry crank-arms 35, 36 which are connected by pitmen 37, 38 to the feed-eccentrics 39, 40 on the main-shaft 6; the feed-advancing eccentric 40 being of the known adjustable type to enable the stitch-length to be regulated.

The throat-plate 18 is formed with feed-dog slots 41 and needle-holes 42 within each of which is preferably provided a depressed shelf 43 having an inclined front edge 44 which deflects to one side the looper-thread leading from the looper-eye to the last stitch, thus assisting in causing the looper-thread to bow away from the looper-blade to open the looper loop for entry by the descending needle. This throat-plate construction is substantially the same as that shown in the U. S. patent to DeVoe No. 1,254,214 of January 22, 1918.

The thread-engaging portions or beaks of the loop-takers 14 and loopers 17 reciprocate in paths at the same side of the respective needle-paths and parallel with the line of feed, hence the loop-takers need have no lateral swells for expanding the needle-loops or shifting such loops laterally to the other side of the respective needle-paths, as would be necessary if the loopers and loop-takers operated at opposite sides of the respective needle-paths. The loop-takers and loopers are two-motion reciprocating members; that is, they have loop-seizing and loop-shedding movements but no sidewise or so-called needle-avoiding movements. Hence the actuating mechanism may be of the simplest character. The free end of the loop-taker shaft 11 and the pin 16 constitute a pair of separated rocker-studs each supporting its complement of stitch-forming members which are of flattened form with thin hubs enabling them to be set close together for narrow-gauge requirements.

The needle-threads are preferably controlled by means of a rotary take-up comprising the spaced parallel disks 7 between which is located the stationary stripper plate 45 having the thread slot 46. A bent wire thread-guide 47 properly positions the needle-threads at either side of the take-up disks 7 for action by the latter.

A thread-nipper is also preferably provided for arresting the feed of the needle-thread during the setting of the stitches. This nipper comprises a nipper-seat 48 and nipper-head 49. The nipper-seat 48 is yieldingly mounted in a recess 50 in the side of the arm 4, being backed by the coil springs 51. The outward movement of the seat 48 under the influence of the springs 51 is limited by the holding screws 52. The nipper-head 49 is fixed to the reciprocating rod 53 journaled transversely of the arm 4 and formed between its ends with a yoke 54 em-

bracing the eccentric follower 55 driven by the eccentric 56 on the main-shaft 6.

The needle-threads lead from the supply to the thread-nipper through a multiple-thread tension device comprising a plurality of thread-tensions 57 mounted on the supporting plate 58 which is held spaced from and fixed relative to a primary supporting plate 59 by means of four corner-posts 60, the plate 59 being carried by a bracket 61 screwed to the top of the arm 4. Slidably mounted on the corner-posts 60 between the plates 58, 59 is the movable plate 62 having mounted on its inner face a disk 63 formed on its exposed face, Fig. 18, with the diametrically opposed cam elevations 64. Mounted in the bracket 61 is a rock-shaft 65 to one end of which is fixed the flanged circular head 66 having cam-depressions 67 receiving the elevations 64 of the disk 63 which are maintained in engagement with the head 66 by means of the bow spring 68, Fig. 16, which is secured between its ends to the plate 58 and presses upon the movable plate 62. When the shaft 65 is rocked the inclined surfaces of the depressions 67 force the movable plate 62 away from the plate 59 and cause the plate 62 to engage the several tension release pins 69 which effect the simultaneous separation of the tension disks of the several pairs.

The shaft 65 is operated by the usual crank-arm 70 and link 71 connected to the usual lifting lever 72 for the presser-foot 73.

It is desirable that the looper-threads run freely in this machine and it is preferred to guide them separately from the looper-thread tensions 74 to the loopers 17. To this end the rear side of the bed 2 is formed with a longitudinally disposed groove 75 in which is removably disposed a multiple thread-guide tube comprising three U-shaped troughs 76 disposed side-by-side and secured together, as by soldering, to constitute a unit which is held in the groove 75 by means of the transverse retainer wires 77 fastened to the cylinder-bed by screws 78. No looper-thread take-up is required.

The stitch-forming cycle is performed substantially as follows. The needles 10 rise, Figs. 5 and 5^a, to throw out their loops which are seized and detained, but are not expanded, by the loop-takers 14. The needles continue to rise and the loopers 17 advance closely above the loop-takers, Figs. 6 and 6^a, in planes substantially coincident with the planes of the respective loop-takers. The loopers 17 enter the needle-loops and pass to the end of their stroke, Fig. 7, while the loop-takers 120 recede and deposit their loops on the loopers. The loopers 17 recede, Fig. 8, and throw out their thread-loops for entry by the descending needles, Fig. 9. The descending needles, together with the take-up 7, tighten the pre-

vious needle-loops as soon as they escape from the loopers.

Having thus set forth the nature of the invention, what I claim herein is:—

5. 1. In a sewing machine, in combination, a reciprocating needle, a reciprocating loop-taker adapted to enter and detain a needle-loop until the needle has risen from the work, without expanding or laterally shifting such loop, an under-thread-looper, and means for 10 moving such looper into the detained needle-loop to carry a loop of under thread through the needle-loop for entry by the descending needle.
15. 2. The combination set forth in claim 1 in which the loop-taker has a loop-engaging portion disposed substantially wholly at one side of the needle-path.
20. 3. The combination set forth in claim 1 in which the loop-taker and looper are arranged to operate in substantially coincident planes wholly at the same side of the needle-path.
25. 4. The combination set forth in claim 1 including feeding mechanism and with the loop-taker and looper arranged to operate in paths parallel to the vertical plane through the line of feed.
30. 5. The combination with multiple-needle mechanism, of a complement of loop-takers and a complement of loop-presenters, separate supports on which said complements are rigidly mounted, each of said loop-takers and loop-presenters being adjustable circularly and longitudinally of its respective support.
35. 6. In a sewing machine, in combination, feeding mechanism, multiple-needle mechanism, a pair of separated rocker-studs, a complement of loop-takers, one for each needle, mounted on one of said studs to suit the gage 40 of the needles, and a complement of loop-presenters, one for each needle, mounted on the other of said studs, each loop-presenter cooperating with its respective needle and loop-taker.
45. 7. In a sewing machine, in combination, a reciprocating needle, a pair of telescopically arranged rock-shafts, a collar secured to the outer of such shafts, a stud carried by said collar in spaced parallel relation with the 50 inner of such shafts, and loop-taker and loop-presenter members secured one to said stud and the other to the inner rock-shaft.
55. 8. A chain-stitch sewing machine having, in combination, feeding mechanism, a reciprocating needle, and looper mechanism comprising a to-and-fro moving loop-taker and a to-and-fro moving loop-presenter, the latter carrying an under-thread and each making one complete to-and-fro movement 60 for each complete reciprocation of the needle, the thread-engaging portions of said loop-taker and loop-presenter operating in substantially coincident planes entirely at the same side of the needle-path and substantially 65 parallel to the line of feed.

9. The combination with a reciprocating needle and a throat-plate, of separately timed two-motion oscillatory loop-taker and loop-presenter elements each making one complete oscillation for each complete reciprocation of the needle, said loop-taker and loop-presenter having beaks extending in opposite directions and operating in paths at the same side of the needle-path and entirely below the throat-plate.

70 10. The combination with a reciprocating needle, and feeding mechanism, of separately timed two-motion oscillatory loop-taker and thread-carrying loop-presenter elements having oppositely directed beaks operating in paths at the same side of the needle-path and parallel to the line of feed, said loop-taker and loop-presenter elements being timed to make one complete oscillation for each complete reciprocation of said needle.

75 11. A sewing machine having a frame including a bed, a hollow standard and hollow overhanging bracket-arm, a main-shaft journaled in said bracket-arm, two eccentrics carried by said main-shaft at the upper end of 80 said hollow standard, a reciprocating needle connected to be operated by said main-shaft, loop-taker and loop-presenter elements, loop-taker and loop-presenter operating rock-shafts journaled in said bed, and two pitmen 85 connections within said standard between said rock-shafts and said eccentrics.

90 In testimony whereof, I have signed my name to this specification.

RUDOLPH BECKER.
